TABULATING, BACK-SPACING, AND KEY-CONNECTING MECHANISM.

1,015,829.

Specification of Letters Patent. Patented Jan. 30, 1912.

Application filed April 10, 1909. Serial No. 489,192.

To all whom it may concern:

Be it known that I, ELEAZAR PARMLY, Jr., a citizen of the United States of America, residing at Washington, in the District of Columbia, have invented certain new and useful Improvements in Tabulating, Back-Spacing, and Key-Connecting Mechanism, of which the following is a specification.

My present invention relates to a combined tabulating, back spacing and key connecting mechanism primarily designed for the equipment of a combined typewriting and adding machine.

The object of the invention is to equip a writing-adding machine with a mechanism operative to retract the carriage across the adding field, to set a tabulating stop in position to arrest the carriage at the proper point for the printing of the next number when the carriage is again moved forward, to connect the keys of the typewriter with the adding mechanism, and to release the carriage for free forward movement with the stop mechanism and the key connecting mechanism in operative position.

Other objects of the invention viewed in various aspects will appear as the succeeding description progresses.

In the accompanying drawings—Figure 1 is a vertical section through an Elliott-Fisher writing-adding machine equipped in accordance with my invention. Fig. 2 is a horizontal section through a portion of the same machine. Fig. 3 is a sectional view of the upper portion of the carriage casing showing one of the numeral keys and part of the mechanism whereby the keys are connected to the adding mechanism. Fig. 4 is a longitudinal vertical section through the carriage of the machine, the keys being indicated in dotted lines. Fig. 5 is a rear elevation of a portion of the carriage showing the two positions of the key connecting arm. Fig. 6 is a diagrammatic view showing the connecting arm 61 in normal position; also showing the normal disconnected position of the numeral keys and the position of the tabulating lever 17 before the latter is moved to connect the keys and to throw down the key connecting arm. Fig. 7 is a similar view showing the parts in the positions they assume when the tabulator lever has been moved to the left, the keys connected, and the arm 61 thrown down to allow the cam

64 to pass under the plate 65. Fig. 8 is still another view of this character showing the parts in the positions they assume after the keys have been connected and after the carriage has moved forward to present the cam 64 under the plate 65. Fig. 9 is a fourth diagrammatic view indicating the manner in which the cam 64 rises when it reaches the end of the plate 65 to effect the disconnection of the keys preparatory to the retraction of the carriage with the cam 64 passing over the plate 65.

The Elliott-Fisher billing-adding machine.—The machine illustrated in the accompanying drawings with my present invention applied thereto is what is known as the Elliott-Fisher billing-adding machine, a combined typewriter and adder of the downwardly printing or flat platen type. The typewriting machine includes a flat platen 1 over which travels longitudinally for line spacing a machine frame 2, supporting a carriage 3 which travels transversely of the platen for letter spacing and supports downwardly acting printing mechanism 4 operated from the numeral keys 5 of the typewriter. The carriage 3 is propelled in the direction of letter spacing by carriage propelling mechanism, not shown, and is controlled by an escapement 6 operated from the keys 5 to permit a step-by-step advance of the carriage. For a more complete description of the machine than is considered necessary for the purpose of this disclosure, reference is made to Patent No. 573,868 to R. J. Fisher.

The tabulating mechanism.—The Elliott-Fisher typewriter is commonly equipped with a tabulating mechanism by means of which the carriage of the machine may be released for free movement and arrested in any desired denominational relation to a predetermined point, as for instance the decimal point of the column. This mechanism includes a pin rail 7 extended along the front of the frame 2 and having a series of pin sockets 8 in any one of which a fixed stop or pin 9 may be placed.

Mounted to slide in suitable guides at the right hand end of the carriage 3 is a movable stop member in the form of a plate 10, the front edge of which is disposed at an angle with respect to the plane of movement of the carriage and is formed with a series of

stepped stops 11. The plate 10 normally occupies a position which presents it out of interfering relation with the fixed stop 9, see Fig. 1, so that the latter opposes no obstruction to the free movement of the carriage. When, however, it is desired to arrest the carriage by means of the tabulating mechanism, the plate 10 is advanced so that, as the carriage advances one of the stops 11 will engage the fixed stop 9. It is obvious that the relation of the carriage to the fixed stop 9 when arrested is determined by the degree of forward movement of the plate 10 and the particular stop 11 thus selected for cooperation with the fixed stop 9.

To facilitate the manipulation of the plate 10 the latter is provided along its left hand edge with a rack 12 engaged by a pinion 13 suitably journaled on the end wall of the carriage 3. The pinion 13 in turn meshes with a toothed segment 14 formed on a disk 15 journaled on a hollow stud 16 screwed into the end wall of the carriage casing, as shown in Fig. 2. The disk 15 is adapted to be oscillated by a tabulator lever 17 fulcrumed at its lower end upon a post 18 outstanding from the disk 15 adjacent to the periphery of the latter. At a point diametrically opposite the post 18 the disk 15 is provided with a lever guide 19 bifurcated to receive the lever, as shown in Fig. 2. This character of mounting of the actuator lever 17 compels the disk to move therewith when the lever is swung forward or back with the axial bearing of the disk as a fulcrum, but enables the lever to be moved laterally with its mounting in the post 18 as a fulcrum. When the lever 17 is swung forward the disk 15 is rotated and motion is thus imparted to the pinion 13 and the stop plate 10, the latter being projected toward its active or operative position. This forward movement of the plate 10 is resisted by a retracting spring 20, see Fig. 1, having connection at its rear end with a fixed part and at its front end with the plates, the shock incidental to the retraction of the latter being absorbed by a cushion 21 with which a pin 22^a on the plate 10 contacts. When the stop plate 10 is advanced to its active position, it is customary to effect the release of the carriage from the control of the escapement so that the carriage may move forward until arrested by the coaction of the stops 9 and 10. To accomplish this a bell crank release dog 22 is mounted inside the carriage casing at the right hand end thereof and its horizontal arm overlies the release lever 23 of the carriage release mechanism which also includes a release key 24 connected to the front end of the lever 23 and by means of which the carriage is released for free movement when the tabulating mechanism is not employed. The vertical arm of the release dog 22 is opposed to the inner end of a sliding release

pin 25 fitted axially in the bearing 16 and opposed at its outer end to the short arm of a sub-lever 26 fulcrumed on the tabulator lever 17.

Associated with the lever 17 is a combined guide and index plate 27 curved concentric to the axis of the disk 15 and having a slot 28 for the accommodation of the lever 17 as the latter is swung forward and back. At one side of the slot the plate 27 is provided with an index 27^a bearing denominational indications as for instance from 1 to 100,000,000, and opposite these indications the plate is provided with notches 27^b to facilitate the accurate positioning of the tabulator lever 17 when the latter is moved forward to any desired denominational position. A second sub-lever 29 is mounted on the lever 17 and has an angular end 29^a interposed between the edge of the guide 85 plate 27 and the upper free end of the lever 26, see Fig. 4. As a result of this arrangement the release of the carriage is effected by the lateral movement of the tabulator lever 17. Thus in operation the lever 17 is thrown forward to project the stop plate 10 and said lever is then swung to the left from the post 18 as a fulcrum. This lateral or release movement of the lever 17 causes it to engage one of the notches 27^b of the index 95 plate and also causes the pin 25 to be moved inward to operate the release dog 22 which in turn operates the release lever 23 to release the carriage and permit the latter to advance freely until arrested by the contacting of one of the stop faces 11 with the stop pin 9.

The back spacing mechanism.—The back spacing mechanism includes a back spacing member in the form of a cam plate 30 imposed upon the stop plate 10 and having an angular front end which constitutes a cam 30^a adapted to coact with a fixed part, as for instance the pin 9, which, in order to reduce the friction incidental to such coaction, is provided with an anti-friction roller 31 with which the cam 30^a engages. In the normal position of the stop plate 10 and the cam plate 30 the latter occupies a relatively advanced position, so that if the two plates are projected in unison, the cam 30^a will contact with the roller 31 and cam the carriage back until the stop plate 10 is located at the left of the stop 9 before said stop plate has been projected into interfering relation with said stop. To cause this simultaneous forward movement of the two plates 10 and 30, they are normally coupled by a coupling pin 32, see Fig. 1, extended through the plate 30 and into a socket 33 in the plate 10. At its upper end the pin 32 is pivotally connected to a trip lever 34 fulcrumed at its rear end upon a stud 35 upstanding from the cam plate 30. The lever 34 is normally held in depressed position by a spring 36 of any 130

suitable form and the front end of said lever is elevated somewhat to permit the post 18 to pass thereunder when the upper end of the tabulator 17 is in a forward position.

- 5 By reason of the connection between the plates 30 and 10 formed by the coupling pin 32, said plates will be advanced in unison when the tabulator lever 17 is moved from its normal position, shown in Fig. 1, to an intermediate position. This forward movement of the tabulator lever 17 will cause the cam plate 30 to coact with the roller 31 and cam the carriage back across the column and will present the tabulator lever adjacent to the upper end of the index 27^a and the post 18 under the front end of the trip lever 34. At this point in the movement of the tabulator lever it is necessary to retract the cam plate 30 out of interfering relation with the roller 31 so that the subsequent forward movement of the carriage will not be obstructed. Therefore the relation of the parts is such that further forward movement of the tabulator lever will cause the post 18 to rise, thus elevating the front end of the trip lever 34 and withdrawing the coupling pin 32 from the socket in the stop plate 10. The connection between the plates being thus broken, the cam plate 30 is retracted by a retracting spring 37 secured at its front end to the plate 30 and at its rear end to one of two bearing brackets 38 extended from the right hand end of the carriage and accommodating both the stop plate and the cam plate. As the forward movement of the lever 17 continues, the stop plate 10 will continue to move forward independently of the cam plate until the selected stop face 11 is moved into position 40 to engage the pin 9 when the carriage is released. It should be understood, however, that in practice the several described operations, to-wit, the camming back of the carriage, the release of the cam plate, and the 45 positioning of the stop plate are all effected by a single forward movement of the lever 17. For instance, the operator has written a number in a column and desires to position the carriage for the next number, which for 50 instance may be 100. He merely moves the tabulator 17 from its normal position, shown in Fig. 1, to a position opposite the hundreds indication on the index plate 27^a. Incidental to such movement of the lever the 55 stop plate 10 and the back spacing cam plate 30 are projected forward in unison to cam back the carriage. While the lever 17 remains in motion, the cam plate 30 is tripped and flies back and as the lever continues forward the continued advance of the stop plate 10 alone, or independently of the cam plate 30, projects said stop plate into operative position. Thus when the lever 17 finally reaches the hundreds indication on the index 65 plate, the carriage will have been cammed

back across the column, the cam plate will have resumed its normal position, and the stop plate will have been positioned to arrest the carriage in the hundreds order of the column as soon as the carriage has been released and permitted to move forward. The operator now presses the upper end of the tabulator lever 17 into the proper notch 27^b of the index plate and incidental to this lateral movement of the lever the pin 25 is forced inward to operate the release mechanism and permit the carriage to jump forward until arrested in proper position by the coaction of the stop plate 10 with the fixed stop 9. The shock incidental to the retraction of the cam plate 30 may be absorbed by a rubber or other suitable cushion 39 secured to the carriage and engaged by a pin 40 on the plate.

The combined tabulating and back spacing mechanism above described is fully disclosed and claimed in my copending application No. 489,191, but is shown herein for the reason that it enters into direct combination with a novel mechanism which 90 serves to connect the numeral keys of the typewriter with the adding mechanism when the lever 17 is manipulated to release the carriage in a manner to be hereinafter explained.

The unit stop.—The Ellictt-Fisher machine is ordinarily equipped with what is known as a single unit stop *a* formed on a swinging stop plate *b* mounted at the right hand end of the carriage and manipulated by a stop key *c* which when depressed moves the stop *a* into interfering relation with the pin 9. The plate *b* is provided with a laterally disposed release arm *d* which overlies the release lever 28 so that when the key *c* is depressed the stop *a* is thrown to its operative position and the carriage is simultaneously released, see Patent No. 723,937 to John A. Smith for a more complete disclosure of this feature of the machine.

The adding mechanism.—As heretofore stated, the Ellictt-Fisher writing-adding machine is a combined typewriter and adder. A sufficient description of the typewriter for the purposes of the present disclosure has been given and it remains to describe briefly the adding mechanism, since the mechanism with which the present invention is most directly concerned is designed 115 to enable the operator, by the manipulation of the tabulator lever 17, to connect the numeral keys of the typewriter with the adding mechanism in addition to the several functions already ascribed to the lever 17.

Mounted on a suitable support in rear of the machine frame 2 is a register or computing device 41 including a series of denominational members 42 and suitable carrying 130

mechanism. One form of register adapted for this use is shown in Patent No. 825,494 to John A. Smith, but the particular register here shown is the subject of the co-pending application of Laganke and Smith, No. 308,279.

Mounted on the typewriter carriage is a master wheel or actuator 43 adapted to engage successive denominational members 42 as the carriage of the typewriter advances step-by-step across the column to which the register 41 has been appropriated. The master wheel 43 is operated from the numeral keys 5 of the typewriter through suitable operating connections each of which imparts to the master wheel a rotary movement corresponding in degree to the value of the particular numeral key operated. One of these operating connections is shown generally in Fig. 1 and it will be seen to include a lever 44 geared to the master wheel shaft 45 and operated by a lever 46 fulcrumed at its rear end, as shown at 47, and provided at its front end with a depending link 48 adapted to swing back and forth. This movement of the link 48 causes a lug 49 thereon to engage or disengage a notched pin 50 projecting from the stem 51 of the adjacent numeral key. For the purpose of swinging all of the links 48 forward to engage the same with the keys 5 an oscillatory key connecting yoke 52 is mounted in the carriage casing and comprises a rock shaft 53 having laterally disposed arms 54 between which is disposed a bar 55 received within longitudinal slots 56 in the links 48.

The mechanism last described, to-wit the master actuator 43 and the connections between the same and the several numeral keys 5, is part of the usual equipment of an Elliott-Fisher writing-adding machine and is disclosed in Patent No. 829,971 to Laganke and Smith, to which patent reference is made for a more detailed showing of the register operating register.

The key connecting mechanism.—In the Elliott-Fisher machine of commerce provision is made for automatically swinging the links 48 into engagement with the numeral keys 5 whenever, in the travel of the carriage, the printing point of the machine moves into the column or adding field and the master actuator 43 moves opposite the register, the numeral keys being unburdened at other times or in other positions of the carriage to facilitate the printing of digits outside of the adding field. A portion of the key connecting mechanism here shown is generally identical with that found in the specified machine the equipment of which heretofore has been in accordance with the disclosure made in Patent No. 863,232 to John A. Smith.

Within the carriage casing is mounted a

yoke operating lever 57 fulcrumed on a support 58 and having its front end in engagement with the bar 55 of the key connecting yoke 52. At the rear end of the lever 57 is mounted an abutment roller 59 shiftable into and out of coactive relation with the front end of a secondary lever 60, the rear extremity of which is extended through the rear wall of the casing to engage a swinging arm 61 mounted in rear of the casing contiguous to what is known in the art as the key connecting arm 62. By means of a connection 63 the arm 61 when depressed or swung down will depress the arm 62 and thus operate the lever 60 and through the latter the key connecting lever 57 which will swing the yoke 52 for the purpose of moving the links 56 into engagement with the notched pins 50 on the numeral key stems.

At the right hand end of the key connecting lever 61 is formed a cam 64 which rides under what is known as the register plate 65, the latter being a small flange or ledge extending forwardly from the register 41 at the bottom thereof. This mechanism, to-wit that train of elements intermediate of the cam 64 and the yoke 52, is identical with the corresponding elements in the Smith patent last referred to, with the sole exception that the rear end of the lever 60 is bifurcated, as indicated at 60^a, and extends both over and under the roller 59 when the latter is in its rearmost or operative position. It may be stated, however, that in accordance with my present invention, the mode of operation of this particular mechanism is somewhat different from that described in the Smith patent as will herein-after more fully appear.

I now come to a description of the essentially novel elements of the structure shown.

Secured to the right hand end of the shaft 53 of the key connecting yoke 52 is a crank arm 66 the wrist 67^a of which is engaged by the bifurcated front end of a lever 67 fulcrumed upon a stud 68 projecting from the right hand end wall of the carriage casing. The rear end of the lever 67 is connected by means of a link 69 disposed vertically, as shown in Figs. 1, 2. and 4, and having its lower end connected with a comparatively long lever 70 disposed alongside of the release lever 23 and fulcrumed as indicated at 71. The lever 70 underlies the horizontal arm of the bell crank release dog 22, see Figs. 2 and 4, and also underlies the release arm *d* of the unit stop *a*.

It will be seen from what has been said that the structure illustrated in this application does not differ from that heretofore proposed, except for the described modification of the rear end of the lever 60 and for the addition of the crank arm 66, the levers 67 and 70 and the link 69. It will, nevertheless, be seen that the mode of manipula-

tion of the machine is materially modified and that the novel elements enter into intimate combination and coaction with the various old elements of the mechanism which 5 have been described with some particularity.

Operation.—When a number has been written in a column and accumulated in the register 41, the printing point of the typewriter will be located at the right of the 10 column and similarly the master wheel 43 of the adding mechanism will be located to the right of the denominational member of lowest order. The operator now swings the tabulator lever 17 forward. This causes 15 the back spacing cam plate 30 to be operated to retract the carriage across the column and the master wheel across the register and continued forward movement of the lever 17 causes the automatic release and 20 retraction of the plate 30 and the subsequent positioning of any one of the stops 11 to coact with the pin 9 for the purpose of arresting the carriage in any selected denominational position of the column when 25 the carriage shall have been released and allowed to move forward, all as described in my application No. 489,191, heretofore referred to. Having thus manipulated the lever 17 to retract the carriage and position 30 the tabulating or carriage arresting mechanism, the lever 17 is swung laterally from the post 18 as an axis. In my above recited application this lateral movement of the lever 17 releases the carriage for forward 35 movement, since the inward movement of the pin 25 will cause the release dog 22 to operate the release lever 23 of the carriage release mechanism. In the present instance, however, this lateral movement of the tabulator lever 17 results in the performance of 40 still another function, to-wit the connection of the numeral keys of the typewriter with the operating mechanism of the register. Thus when the lever 17 is swung to the left, 45 the consequent operation of the release dog 22 depresses the front ends of both the carriage release lever 23 and the lever 70 of the key connecting mechanism. This operation of the lever 70 causes the latter to elevate 50 the rear end of the lever 67 through the medium of the link 69 and swings the crank arm 66 which in turn rocks the shaft 53 and causes the key connecting yoke 52, of which said shaft is an element, to throw the links 55 48 forward and into engagement with the stems of the numeral keys 5. By the manipulation of the lever 17 the operator has now cammed the carriage back across the column, positioned a tabulator stop, released 60 the carriage for forward movement, and connected the keys of the typewriter with the adding mechanism. Incidental to the connection of the keys the levers 56 and 60 have been operated to depress the arms 61 65 and 62, so that the cam 64 on the lever 62,

instead of being depressed by the register plate 65 upon the advance of the carriage, will be sufficiently lowered to pass under said plate. The released carriage will now move forward until arrested by the tabulator stops in proper position for the writing and adding of the next number. When the carriage is thus positioned the tabulator lever and the stop plate 10 fly back to their normal positions, as usual, and incidental to this retraction of the parts the key yoke 52 is released and would likewise be retracted by its spring α were it not for the fact that the cam 64 on the lever 62 having been depressed by the manipulation of the lever 17, will have passed under the plate 65 and will now be held down by said plate as long as the printing point of the carriage is in the column and as long as the master wheel is opposite the register. The carriage having now been properly positioned and the keys having been connected with the adding mechanism, the operator proceeds to write the number in the column and to accumulate the same in the register. As soon as the machine passes beyond the column, the cam 64 will ride out from under the right hand end of the register plate 65 and the retracting spring α of the key connecting yoke will incidentally retract the yoke to disconnect 90 the keys from the adding mechanism by withdrawing the links 48 from engagement with the stems of the numeral keys. Thus it will be seen that by the manipulation of a single element, to-wit the tabulator lever 100 17, the carriage is retracted, the tabulating mechanism is positioned, the keys are connected with the adding mechanism, and the carriage is released in order to permit its instant advance to the proper position for 105 the writing of the next number.

If it is not desired to utilize the variable tabulating mechanism and the carriage retracting mechanism, the unit stop key α may be depressed to position the unit stop α 110 and simultaneously release the carriage and connect the keys with the adding mechanism, since it will be obvious from what has been said, and by reference to Fig. 2 of the drawings, that the depression of the 115 stop key α will not only swing the stop α into a path obstructed by the pin 9, but will also depress the front ends of the carriage release lever 23 and the key connecting lever 70.

By the employment of the mechanism described, the manipulation of a writing-adding machine is materially simplified and the speed of operation increased. The possibility of error is furthermore minimized 125 because if it is desired to print digits in the adding field without operating the register, as for instance in writing in a heading or the like, it is not necessary for the operator to disconnect the keys from the adding 130

mechanism and remember to subsequently reconnect the parts for addition. On the contrary, the tabulating mechanism, which is invariably employed when adding in the 5 column, will insure the proper connection of the keys with the adding mechanism and in order to print headings and the like without adding, it is merely necessary for the operator to advance the carriage to the proper point by the manipulation of the release key 24, or the space bar, or in any 10 other manner which does not involve the manipulation of the tabulating mechanism. This is true for the reason that the cam 64 15 on the key connecting arm 61 instead of normally occupying a position which will present it to the plate 65, is elevated in accordance with my invention so that normally it occupies the position shown in Fig. 6, which will permit it to pass over the plate 65 when the carriage moves forward unless the arm 61 has previously been thrown down by the operation of the lever 17. It will appear, however, that should it be desired 20 to use the machine for straight typewriting, as for instance tabulation without addition, and to employ the tabulating mechanism to facilitate said work, the entire key connecting mechanism may be put out of action by 25 simply withdrawing the roller 59 out of co-operative relation with the lever 60 by the manipulation of the total key in the usual manner.

It is thought that from the foregoing, the 30 construction, operation and advantages of my invention will be fully comprehended, but I wish to be understood as reserving the right to effect such modifications of the illustrated structure as may come fairly within 35 the scope of the protection prayed.

What I claim is:—

1. The combination with keys and adding mechanism, of means for changing the denominational relation of the keys and adding mechanism, selecting mechanism operative to determine such relation, means for operatively connecting the keys with the adding mechanism, and a connection between the selecting mechanism and the key 45 connecting means.

2. In a combined typewriting and adding machine, the combination with a typewriter including a carriage, keys and printing mechanism, of an adding mechanism normally disconnected from the keys, key connecting mechanism operative to connect the keys and adding mechanism, a tabulating mechanism for arresting the carriage, and a connection between the tabulating mechanism and the key connecting mechanism.

3. The combination with a key-operated recording mechanism, a carriage movable to determine the position of the record on the work sheet, an adding mechanism, means 65 for connecting the keys with the adding

mechanism, a stop movable into and out of position to arrest the carriage, and controlling means common to said stop and to the key connecting mechanism.

4. The combination with recording mechanism, keys for operating the same, and a movable carriage, of adding mechanism, key connecting means operative to establish a co-operative relation between the keys and adding mechanism, tabulating mechanism 70 including a movable stop and an operating device for said stop, and means whereby the connection between the keys and adding mechanism is controlled by the stop operating device.

5. The combination with recording mechanism and keys, of an adding mechanism, a carriage movable to change the denominational relation of the keys and adding mechanism, and combined tabulating and key 80 connecting mechanism operative to establish a co-operative relation between the keys and adding mechanism and to select the denominational relation thereof.

6. The combination with a typewriter including a carriage, keys and printing mechanism, of an adding mechanism, key connecting mechanism operative to connect the keys and adding mechanism, said key connecting mechanism being manually operative, and means whereby the disconnection of the keys and adding mechanism is effected by the movement of the carriage.

7. In a combined typewriting and adding machine, the combination with a carriage, 100 keys and printing mechanism, of an adding mechanism normally disconnected from the keys, key connecting mechanism for connecting the keys and adding mechanism, carriage retracting mechanism, and controlling means common to the key connecting and carriage retracting mechanisms.

8. The combination with a carriage, keys and printing mechanism, of an adding mechanism, means whereby the movement of the 110 carriage will control the denominational relation of the keys and adding mechanism, key connecting mechanism movable to connect the keys and adding mechanism, carriage retracting mechanism, and operating 115 means common to the key connecting mechanism and the carriage retracting mechanism.

9. The combination with a carriage, keys and printing mechanism, of an adding mechanism, means whereby the denominational relation of the keys and adding mechanism will be controlled by the movement of the carriage, key connecting mechanism, means normally restraining the carriage, carriage release mechanism, and controlling means 120 common to the key connecting and carriage release mechanisms.

10. The combination with a carriage, keys and printing mechanism, of an adding mech- 130

- anism, key connecting mechanism movable to connect the keys and adding mechanism, means normally restraining the carriage, carriage release mechanism, and a member movable to operate both the carriage release mechanism and the key connecting mechanism.
11. The combination with a carriage, keys and printing mechanism, of an adding mechanism, key connecting mechanism, carriage retracting mechanism, and a stop mechanism movable into position to arrest the carriage, and controlling means common to the key connecting mechanism and carriage retracting mechanism and the stop mechanism.
12. The combination with a carriage, keys and printing mechanism, of an adding mechanism normally disconnected from the keys, key connecting mechanism operative to connect the keys and adding mechanism, means normally restraining the carriage, carriage release mechanism, carriage retracting mechanism, carriage arresting mechanism, and controlling means common to the key connecting, carriage releasing, carriage retracting and carriage arresting mechanisms.
13. The combination with a carriage, keys and printing mechanism, of an adding mechanism normally disconnected from the keys, key connecting mechanism movable to connect the keys and adding mechanism, means normally restraining the carriage, carriage release mechanism, mechanism operative to retract the carriage, stop mechanism movable into position to arrest the carriage upon the forward movement thereof, and a member movable in one direction to cause the operation of the carriage retracting and stop mechanisms and in another direction to cause the operation of the key connecting and carriage releasing mechanisms.
14. The combination with a typewriter including a carriage, keys, printing mechanism and tabulating mechanism, of adding mechanism normally disconnected from the keys, and means controlled by the tabulating mechanism to establish a coöperative relation between the keys and adding mechanism.
15. The combination with a typewriter including a carriage, printing mechanism and tabulating mechanism, of adding mechanism normally disconnected from the keys, means controlled by the tabulating mechanism to establish a coöperative relation between the keys and adding mechanism, and means independent of the tabulating mechanism for maintaining the key connecting mechanism in position to connect the keys and adding mechanism.
16. The combination with keys and adding mechanism normally disconnected therefrom, of key connecting means operative to connect and disconnect the keys and adding mechanism, a traveling carriage, carriage arresting means, and a connection between the carriage arresting means and the key connecting means.
17. The combination with adding mechanism, normally disconnected keys, and key connecting mechanism, of a carriage movable to change the denominational relation of the adding mechanism and keys, coacting stops for arresting the carriage, stop positioning means, and means associated with the stop positioning means for controlling the key connecting mechanism.

In testimony whereof I affix my signature in presence of two witnesses:

ELEAZER PARMLY, JR.

Witnesses:

J. FRANK CULVERWELL,
D. A. COLNE.
